Primary Examiner — Selina Sikder*(74) Attorney, Agent, or Firm* — James F. Hann; Haynes Beffel & Wolfeld LLP(57) **CLAIM**

The ornamental design for a foot actuated controller, as shown and described.

DESCRIPTION

FIG. 1 is a perspective view of a foot actuated controller showing our new design;

FIG. 2 is a top plan view thereof;

FIG. 3 is a front elevation view thereof;

FIG. 4 is a right side elevation view thereof;

FIG. 5 is a left side elevation view thereof;

FIG. 6 is a rear elevation view thereof;

FIG. 7 is a bottom plan view thereof; and,

FIG. 8 is a cross-sectional view taken along line **8-8** of FIG. the 2 showing surface shapes.

The broken lines are for the purpose of illustrating portions of the foot actuated controller and form no part of the claimed design.

The foot actuated controller is used to control operations of a catheter during a medical procedure.
